UNITED STATES PATENT OFFICE

149,084

DESIGN FOR A SHRIMP KNIFE

Robert W. Nelson, Minneapolis, Minn.

Application July 31, 1946, Serial No. 132,150

Term of patent 3½ years

(Cl. D22—3)

To all whom it may concern:

Be it known that I, Robert W. Nelson, a citizen of the United States and a resident of Minneapolis, in the county of Hennepin and State of Minnesota, have invented a new, original, and ornamental Design for a Shrimp Knife, of which the following is a specification, reference being had to the accompanying drawing, forming part thereof.

Referring to the drawing:

Fig. 1 is a top plan view of a shrimp knife showing my novel design;

Fig. 2 is a side elevational view thereof; and

Fig. 3 is an end elevational view thereof.

I claim:

The ornamental design for a shrimp knife, substantially as shown.

ROBERT W. NELSON.
